UNITED STATES PATENT OFFICE.

SALEM LEON SCHLEPPY, OF CHICAGO, ILLINOIS.

PUMP.

Application filed November 18, 1920. Serial No. 424,916.

To all whom it may concern:

Be it known that I, SALEM LEON SCHLEPPY, a citizen of the United States, residing at Chicago, in the county of Cook and State 5 of Illinois, have invented certain new and useful Improvements in Pumps, of which the following is a description.

The primary object of my invention is to provide a device of this character having 10 maximum efficiency and being highly reliable in operation. Among other objects and advantages of the pump herein disclosed are the production of a pump having high volumetric efficiency, lightness of construction, little friction or slippage loss, and low power consumption. Another object of 15 my invention is to produce a pump in which the delivery of fluid is practically continuous and free from those pulsations caused by 20 pumps having an intermittent delivery.

My invention contemplates the use of a series of impeller vanes driven continuously and uniformly, drawing fluid between them, and acted upon by means which greatly decreases the fluid-chamber between the successive vanes as they pass the discharge ports thus compressing and expelling fluid into these ports, and then increasing the fluid chambers between the vanes as they pass the 25 intake port, thus expanding the fluid into these chambers.

With the foregoing and other objects in view, my invention consists in the combination and arrangement of parts herein disclosed and shown and more particularly pointed out in the claims, but it is to be understood that changes in the precise embodiment shown and described may be made 30 without departing from the spirit of the 40 invention as claimed in the claims hereunto appended.

Referring more particularly to the drawings, in which like reference characters indicate the same or similar parts throughout the views.

Figure 1 is a vertical longitudinal section of the pump;

Figure 2 is a vertical section taken at right angles to Figure 1, on the line 2--2 of 50 Figure 1;

Figure 3 is a fragmentary section taken on line 3--3 of Figure 4;

Figure 4 is an elevation on the line 4--4 of Figure 2 with one of the bearing plates 55 removed.

Figure 5 is an elevation of the driving gear assembly.

In the drawings 1 designates the cylinder or casing of the pump which is preferably provided with end plates 2 and 3, said end plates being secured to the casing by screws 4, or other suitable equivalent means. Located in the casing wall are one or more pairs of intake and discharge ports, the intake and discharge ports being alternately arranged. In the embodiment shown, I have indicated two intake ports 5 and 5', and two discharge ports 6 and 6'. Suitable conduits 7 lead to the intake ports as shown, said conduits leading the fluid to the pump from any suitable source of supply.

The pump is provided with a pair of drive shafts 8 and 9 which are so geared together that they are driven in unison and drive the sprocket wheels 10 and 11. These drive shafts 8 and 9 are extended through the casing so as to drive a pair of sprockets which are duplicates of the sprockets 10 and 11 and arranged on the opposite end of the drive shafts. Each of the duplicate pairs of sprockets drives a series of rollers 15, at the ends of pivot pins 16 extending across the casing.

Mounted upon stub shafts 17 at each side of the casing, are pairs of idlers 18, (see Figures 3 and 4), said idlers being arranged at both sides of the rollers, as shown in Figure 4. It is to be noted that the pitch lines of the idlers are not in alignment with the pitch lines, of the drive sprockets but are arranged at one side of this line so that they engage the rollers and move them transversely or inwardly of said line as they leave the drive sprockets, for a purpose to be hereinafter described.

Arranged within the casting and mounted on the pins 16 are a series of rigid impeller vanes or blades A, the bases of these vanes being offset, as at 19, so as to form links extending rearwardly of the direction of travel of the vanes, each of the vanes being pivotally secured to adjacent pivot pins at two parallel spaced axes, one near each of the ends of the offset bases or links. These offset bases are also formed with cutaway or recessed portions at their ends so as to interlock with the cutaway ends of adjacent vanes, as shown in Figure 2, wherein 20 indicates the offset portions of one vane and 21 indicates the mating or interlocking portions of 110

the adjacent vanes, thereby enabling adjacent vanes to be connected or linked together on the same pivot pins 16 and forming an endless chain of impellers. I have called 5 these combined impellers and links by the term of "link impellers" as signifying that the impellers are linked together, just as the links of a chain are joined.

Reinforcing ribs 22 are provided on the 10 rear faces of each of the vanes A. Secured to the vanes in any suitable manner, as by brazing, soldering, riveting, etc., are a series of backing plates 23, extending entirely across the cylinder between the end plates 15 2 and 3, each backing plate being joined to the rear or trailing face of the vane tip and diverging inwardly therefrom toward the rear of the offset base of the vane, to which it is secured. Thus there is a backing plate 20 secured to the tip and to the base of each vane. By the use of such a backing plate there is provided a space substantially triangular in outline between the forward face of one vane and the backing plate of the adjacent vane, which greatly reduces the "dead air" space which would otherwise occur at 25 the lower portion of the fluid-receiving pocket, (see Figure 1).

Figures 2 and 5 illustrate the driving connection between the sprocket wheels and any suitable source of power.

The drives may be of any suitable type, such as gears, chains or the like, but in the embodiment shown I prefer to use a driving shaft 24 having a gear wheel 25 at its end, which meshes with and drives a pair of parallel spaced gears 26 and 27, mounted on the driving shafts 8 and 9 respectively upon which the sprocket wheels are mounted. 30 Thus it is apparent that as the gears 26 and 27 are rotated in unison by the driving gear 25, they will rotate in the same direction and drive the two duplicate pairs of sprocket wheels to actuate the rollers and the linked vanes carried by the pins 16.

Antifriction bearings 28 are provided at the journaled ends of each of the shafts 8 and 9, the idler 18 being also mounted on antifriction bearings 29. Removable cover plates 30 are provided for enclosing the drive elements and which facilitate access to the drive mechanism, for assembling or repair.

Referring more particularly to Figure 1, in which the direction of flow or fluid is indicated by arrows, it will be seen that the fluid is received in the chambers between the spaced vanes at the intake port 5, and compressed or discharged at the next discharge port, by decreasing the size of the fluid chambers. The vanes continue their cycle, and as they leave the discharge port are separated or expanded to increase the size of the fluid chambers between them and draw fresh fluid in at the next intake port 5, said fresh fluid being compressed and ex-

10 pelled at the next discharge port 6'. The compressing and expelling action is caused by the idlers 18 acting upon the rollers and the pivotally outer connected vanes A, and which positively moves the vanes together 15 at the discharge ports, and allows them to separate at the intake ports.

Each vane, being pivoted at its base will swing about its pivot as the rollers 15 pass under the idlers and are forced inwardly. 20 The tip of one pivoted vane will be swung toward the tip of the adjacent vane and thus compress and expel the fluid trapped between the backing plate of one vane and the forward side of the adjacent vane, into the 25 discharge port.

The cylinder wall is offset internally at the discharge ports, as at 31, to form surfaces which will bear against the vanes as they are swung inwardly on their pivots at 30 the discharge ports, and will prevent leakage between the vanes and casing. As the vanes approach the intake ports they separate and enlarge the chambers between them, causing the fluid entering through said ports 35 to be expanded into the spaces or chambers between the adjacent vanes, where it is carried to the next exhaust port and the vanes are acted upon by the idler wheel to discharge the fluid, after which the vanes again 40 separate to take in fresh fluid at the next intake port, the fluid expelled at the next discharge port, and so on indefinitely.

The action of compressing and expelling the fluid from between the vanes at the discharge ports is similar to the action caused by rapidly flitting together the leaves of a book.

It will be particularly noted that while two pair of ports are shown, the number of pairs may be increased indefinitely by simply making the casing of sufficient length and providing sufficient numbers of link-impeller vanes, and also providing idlers at each of the discharge ports. Then, as in the embodiment shown, the idlers will actuate the tips of the vanes together to discharge the fluid between them at each discharge port, the action of the pump being substantially continuous, the fluid being received and discharged in a substantially continuous stream.

What I claim as new and desire to secure by Letter's Patent is:

1. In a device of the kind described and in combination, a casing having intake and discharge ports, a series of spaced link-impeller vanes in said casing, pivot pins pivotally connecting said vanes to each other, rollers on said pins, a pair of drivers engageable with said rollers to drive said link-impeller vanes, an idler in the path of said rollers intermediate the drivers and having its pitch line out of alignment with the pitch lines of the drivers, whereby the roll- 120

125
130

ers are engaged by said idler to tilt the vanes intermediate the drivers and bringing them together to expel the fluid between them.

2. In a device of the kind described and in combination, a casing having intake and discharge ports, a series of spaced link-impeller vanes in said casing, pivot pins pivotally connecting said vanes to each other, rollers on said pins, a pair of drivers engageable with said rollers to drive said link-impeller vanes, an idler in the path of said rollers intermediate the drivers and having its pitch line out of alignment with the pitch lines of the drivers, whereby the rollers are engaged by said idler to tilt the vanes intermediate the drivers and positively move them transversely of said idler, whereby the free ends of said vanes are brought toward each other to expel the fluid between them.

3. In a device of the kind described and in combination, a casing, a series of spaced impeller vanes pivotally linked together in said casing, an intake port for admitting fluid into the spaces between said vanes, an outlet port, a pair of drivers, an idler between said pair of drivers, drive rollers on said linked vanes, said rollers being actuated by said drivers and engageable with said idler, said idler being out of alignment with said drivers, whereby the rollers are positively moved transversely to said alignment line and causing the vanes to move transversely to said line, whereby said vanes are brought toward each other to expel the fluid between them.

4. In a device of the character described and in combination, a casing having a series of intake and discharge ports alternately arranged therein, a series of impeller vanes in said casing movable continuously past said ports in sequence, and separate means for positively moving the vanes to decrease the spaces between adjacent vanes at said discharge ports.

5. In a device of the kind described and in combination, a casing, a series of spaced impeller vanes in said casing, each of said vanes having a base offset therefrom, backing members secured to the back of each of said vanes and converging to the tips of said vanes, an intake port for admitting fluid into the spaces between each of said vanes, and the backing member of the adjacent vane, an outlet port, means for actuating said vanes whereby they are moved toward each other at said discharge port to expel the fluid between them into said discharge port.

6. In a device of the kind described and

in combination, a casing, a series of link-impellers in said casing, said impellers being linked together to form a continuous chain, an intake port for admitting fluid into the spaces between said impellers, an outlet port, a pair of pinions for driving said link-impellers past said ports, and separate means intermediate said pinions and positively engaging said chain to decrease the spaces between said impellers at said outlet port.

7. In a device of the kind described and in combination, a casing having an intake and a discharge port therein, a series of link-impellers in said casing, linked together to form a continuous chain, means for driving said link-impellers past said ports in sequence, and means for decreasing the space between adjacent impellers at said discharge port, said casing having an inwardly projecting convex portion engageable with said impeller tips at said discharge ports.

8. In a device of the kind described and in combination, a casing having an intake and a discharge port therein, a series of link-impellers in said casing, linked together to form a continuous chain, a pair of spaced driving pinions drivingly engageable with said link-impellers to drive them past said ports in sequence, said pinions spaced apart a sufficient distance so that said impellers are free of engagement with said pinions at said discharge port, and means independent of said driving pinions for decreasing the space between adjacent impellers at said discharge port.

9. In a device of the kind described and in combination, a casing having an intake and a discharge port therein, a series of link-impellers in said casing pivotally linked together to form a continuous chain, each link-impeller comprising a vane portion with a link-portion base extending transversely of said vane portion, means for driving said link-impellers past said ports in sequence, and means for rocking said impellers on their pivotal axes at said discharge port to decrease the space between the adjacent vanes, the tips of said vanes being arranged to extend forwardly in the direction of travel beyond either of said pivotal axes of the bases of said impellers.

In testimony whereof, I have hereunto signed my name in the presence of two subscribing witnesses.
